UNITED STATES PATENT OFFICE.

MILES H. MANN, OF TERRE HAUTE, INDIANA, ASSIGNOR, BY MESNE ASSIGNMENTS, TO REMINGTON ARMS COMPANY, INC., OF NEW YORK, N. Y., A CORPORATION OF DELAWARE.

MONEY-PAYING MACHINE.

Application filed October 18, 1916. Serial No. 126,393.

To all whom it may concern:

Be it known that I, MILES H. MANN, a citizen of the United States, residing at Terre Haute, in the county of Vigo and State 5 of Indiana, have invented certain new and useful Improvements in Money-Paying Machines, of which the following is a specification.

My present invention appertains particularly to money handling machines and consists primarily of an improvement in a machine designed for the paying out of paper money in predetermined amounts susceptible of being varied by the control 10 of manipulable devices of any suitable construction.

More specifically speaking, the improvement of this invention appertains to the wage paying machine shown and described in 20 U. S. Letters Patent of A. Von Barth, No. 1,114,828, issued October 27, 1914, in which machine there is provided a slow moving conveyer adapted to convey a bill or bills supplied thereto, to a suitable point of discharge or delivery, the action of the conveyer being pneumatic in so far as carrying the paper currency is concerned.

In regard to the pneumatic phase of the operation of the conveyer mechanism set 30 forth in said Letters Patent, it may be noted that air suction acting in connection with certain elements of the conveyer is intended to cause adherence, or to connect, a bill or bills of paper currency with respect 35 to the conveyer, the suction acting to maintain said connection between the paper currency and conveyer until the bill or bills are removed or detached from said conveyer for discharging purposes.

40 The essential feature of this invention resides in the provision of positive acting means co-operative with the conveyer of a machine of the construction embodied in the Letters Patent above identified whereby to insure the separation of the paper money 45 from the conveyer at the proper time when the delivery or discharging of the money from the machine is required to be performed.

50 A complete comprehension of the construction and operation of my invention will be had upon reference to the Letters Patent previously referred to and to the following detailed description, supple-

mented by the accompanying drawings, in which:

Figure 1 is a horizontal sectional view of the conveyer and suction casing of a machine of the type to which the invention appertains, the section being taken about 60 on the line 1—1 of Figure 2, and the shutters as well as conveyer chains being only partially illustrated or entirely omitted in the view.

Figure 2 is a vertical longitudinal section taken about on the line 2—2 of Figure 1, a couple only of the bill holding and supplying holders or pockets being illustrated.

Figure 3 is a fragmentary sectional view somewhat exaggerated in size in order to 70 bring out more fully the construction of the stripping means of the invention.

It is not believed necessary to describe in detail the general construction and operation of the machine to which the present 75 improvements are intended to be applied since for this purpose the Von Barth Letters Patent hereinbefore mentioned is made a part of this specification and may be consulted in connection with the following description and the illustrations of the drawings forming a part hereof. It suffices to state that the general operating features and controlling parts of the machine to which the present improvements 85 are applied are the same as shown and described by Von Barth excepting where structural differences or additions are proposed as hereinafter disclosed.

90 In the drawings A denotes a suction casing in which is mounted the conveyer or carrier of the same general construction as shown in Von Barth's patent, the casing being provided at its upper portion with an opening and there being connected at said 95 opening a pipe or conduit B leading to any suitable air suction creating means such as an exhaust pump, fan, or the like.

100 The carrier located in the casing A is comprised of suitable sprocket chains 1 passing around sprocket wheels 2 carried by shafts 3, the chain 1 being built up of links and pivots, and the pivots, designated 4, preferably consisting of rods extending from one side to the other of the casing 105 A. Upon each of the pivots or rods 4 is mounted a louvre or shutter 5 adapted to turn freely about the rod and consisting of

a piece of sheet metal or other material of a substantial width so that each shutter will extend from its own pivot to rest upon the succeeding shutter, thereby substantially 5 but not entirely closing the space between the rods against the flow of air.

Beneath the casing A and disposed in an opening in a table C which really forms the base of the casing A are any suitable number 10 of bill holders or pockets, the latter being of the type shown in the said Letters Patent and capable, therefore, of delivering bills to the carrier in the casing A, as an incident to raising or upward movement of the bill 15 pocket actuated by any suitable mechanism. If a selected bill pocket or pockets D be raised in the operation of a machine such as above set forth, fingers 6 at the upper end of each bill pocket will engage projections 7 at 20 the ends of the shutters 5, thereby raising and opening the shutters slightly, so as to cause the topmost bill in each elevated pocket or holder D to be held against the carrier and thus withdrawn from the pocket as the 25 latter moves back to its normal position. There is always sufficient leakage of air between the abutting portions of the shutter 5 to cause the bill or bills delivered to the carrier to sufficiently adhere to the latter as 30 to be carried along with it in the direction of the arrow in Figure 2, the intention being to deliver the bill or bills thus caught up by the carrier to the point of discharge approximately at E in Figure 2, and above the 35 recess F in the table C.

In a machine of the type of the present invention it is prerequisite that each operation of detaching a bill from its respective pocket D, and delivering said bill to the discharge 40 be absolutely insured for otherwise the machine would be without utility. In other words, accuracy in the paying action of the machine is not merely desirable but wholly a proposition of necessity.

45 Since a machine such as proposed in the previously referred to patent of Von Barth, and proposed in my construction employs no provision to insure the delivery of the bills from the pockets A to the carrier in the casing A, at any predetermined point in the length of said carrier, the possibility exists that the suction in the casing A will draw the forward or delivery edge of a bill upwards between the rods or pivots 4 of the 50 shutters 5 so as to make impossible the delivery of the bill at the discharge aperture of the casing A, according to the construction in said Letters Patent. The foregoing 55 is true whether the carrier be constructed with the shutters 5, or the shutters dispensed with and the carrier constructed as disclosed in Figure 9 of said Letters Patent.

60 I will now describe the means utilized by me for insuring the proper delivery of the bills supplied to the carrier in the casing A

under all conditions of service of the paying machine. Referring especially to Figures 2 and 3, it will be observed that I employ a plurality of endless belts 7 located at intervals of space from one another the entire 70 width of the casing A and passing around the various pivot rods 4 in such a manner that these belts turn with the conveyer and form elements of the conveyer. In order that the belt will travel in properly spaced 75 relation, I contemplate providing at one end of the casing A a plate 8 having apertures through which the belts or endless members 7 travel. The opposite end of the casing A 80 adjacent to the recess F of the table, and the discharge E, is formed with stripping fingers 9 at intervals, the lower ends of said fingers terminating proximate to the discharge and there being an aperture 10 some distance away from the somewhat pointed 85 extremity of each finger, through which aperture an adjacent endless member 7 is adapted to travel in a manner similar to its movement through the apertures of the plate 8. It is contemplated to provide a sufficient 90 number of the members 7 to maintain the bill, adhering to the carrier in the casing A when delivery is being made, in a substantially flat position, but especially in a condition such that its forward edge will be 95 engaged by the stripping fingers 9 and positively separated from the conveyer owing to the fact that the endless members 7 travel on the outer sides of the stripping fingers 9 and positively carry the forward edge of 100 the bill out of the casing 8 at the discharge opening of the latter. Figure 3 depicts the manner in which the endless members 7 operate exterior to the fingers 9, and pass back into the casing A at the aforesaid apertures 105.

110 It is not thought necessary to describe the advantages of the improvement above set forth as the same will be appreciated having in view the foregoing description and a study of the operation of a paying machine of the type improved upon. It may be stated, however, that my invention contemplates broadly the provision in association with a carrier or conveyer in a suction casing such as A, of means at the discharge of 115 said casing for positively separating the bill or paper currency in process of conveyance from the conveyer to insure delivery, such means, of course, acting in opposition to the tendency of the suction through the elements of the conveyer and through the discharge opening itself to prevent the bill from being delivered at the proper place and at the proper time.

120 Having thus described my invention, what I claim as new is:

1. In a money paying machine, the combination with a casing, a carrier movable in said casing, a suction conduit connected with 130

and longitudinally of the casing, said casing being provided with means for guiding said belts in their movement with the carrier whereby to maintain the belts in proper spaced relation.

7. In combination, a bill holder and a carrier associated therewith, means whereby to cause the carrier to remove a bill from the

holder and carry the same to a point of delivery, and means on the carrier for deflecting the bill at the point of delivery in such a manner as to positively separate the bill from the carrier.

In testimony whereof I affix my signature.

MILES H. MANN.
